163,844

SOUVENIR PLAQUE

Steve Bazur and George W. Kaiser, Reno, Nev.

Application March 3, 1950, Serial No. 8,292

Term of patent 3½ years

(Cl. D29—23)

To all whom it may concern:

Be it known that we, Steve Bazur and George W. Kaiser, both citizens of the United States, and both residing at Reno, in the county of Washoe and State of Nevada, have invented a new, original, and ornamental Design for a Souvenir Plaque, of which the following is a specification, reference being had to the accompanying drawings, forming a part hereof.

We claim:

The ornamental design for a souvenir plaque, as shown.

STEVE BAZUR.
GEORGE W. KAISER.
